UNITED STATES PATENT OFFICE.

FREDERIC C. WILLIAMS, OF CORONADO BEACH, CALIFORNIA.

VALVE TURNING AND GRINDING MACHINE.

1,416,920.

Specification of Letters Patent. Patented May 23, 1922.

Application filed July 1, 1920. Serial No. 393,400.

To all whom it may concern:

Be it known that I, FREDERIC C. WILLIAMS, a citizen of the United States, and a resident of Coronado Beach, in the county of San Diego and State of California, have invented certain new and useful Improvements in Valve Turning and Grinding Machines, of which the following is a specification.

My invention relates to means for turning and grinding valves such as are used in internal combustion engines and the like and the primary object thereof is to provide a machine which will readily and easily accomplish this purpose with the greatest precision.

Valves of this class are usually finished and refinished in lathes and in order that the angle of the valve may perfectly correspond to and fit into the valve seat a great amount of time is consumed in setting up the machines, and the same is true when the valves are ground. Not every shop is equipped with the necessary machine tools for refinishing the valves, and a further object of this invention is to provide a small machine of simple structure which may be provided at a moderate price for small shops for accurately forming and finishing the valves.

The angle of the valves at the valve seat is usually about 45 degrees, and in order to provide against leakage at the valve, and thus afford the maximum efficiency of the engine, it is necessary to have the valve exactly correspond to the valve seat in dimensions and form, and to provide against inaccuracy in setting up the valve for finishing, I provide means for holding the valve firmly in position in the machine and means for holding the tool in adjustable working relation with the valve, the tool being supported at the proper angle relative to the valve supporting spindle, thus providing means for quickly finishing the work and rendering it possible to finish or refinish a large number of valves in a short length of time.

A further object is to provide the tool holder of the machine with means whereby the turning tool may be quickly replaced with a grinding element capable of being driven by power, without disturbing the relative positions in the machine of the tool holder and valve supporting means. Other objects will appear as the description progresses.

Referring to the drawings, in which similar characters of reference indicate the same parts throughout the specifications and the several views of the drawings, Fig. 1 is a plan of my machine; Fig. 2 is an elevation of the same; Fig. 3 is an end elevation of the same; Fig. 4 is a transverse sectional elevation of the same on the line 4-4; Fig. 5 is a section of the tool holder, and body; Fig. 6 is a transverse section of the same forward of the body; Fig. 7 is a sectional plan of a modified form of tool holder, showing the grinding means supported therein; Fig. 8 is a transverse section of Fig. 7 on the line 8-8; and Fig. 9 is a longitudinal section of the same.

The flat base 1 has a pair of main bearings 2 and 3 supported thereon by means of ribs 4 and 5, to which are attached at the top the top removable bearing members 2' and 3', respectively, by means of studs 6 and wing nuts 7, each of the bearings having a bushing 8 which is tightly held between the upper and lower bearing members when the nuts 7 are tightened on the studs 6.

A valve spindle 9 is revolvably supported in the bushings 8 of the bearings 2 and 3 and is provided at the rear end with a crank 10 held thereon by means of a screw or bolt 85 11 secured to the lugs 12 on the crank, or otherwise. The forward end of the spindle is substantially extended forward of the bearing 3 and has a conical bore 13 in the end to receive the conical end of the pivot 90 adjusting screw 14 which is threaded through the boss 15 at the front end of the base supported on ribs 16 and 17, a lock nut 18 being provided on the screw 14 for locking the screw against longitudinal movement.

The angle of the pivot seat in the end of the spindle 9 conforms substantially to that of the end of the screw 14 and a minimum amount of friction will be encountered in the turning of the spindle of arbor 9 by means of a slight taper on the end of the spindle, or, by other means, a collar 20 being placed on the spindle at the rear of the valve between which and the front side of the bearing 3 a spring 21 is compressibly held on the spindle for forcing the valve forward thereon and holding it in such position during the turning and grinding operation.

A horizontal extension 22, forming a tool holder, is integral with and is connected

with the base 1 by means of ribs 23 and 24. This extension is disposed at an angle of 45 degrees, or any suitable angle, relative to the longitudinal axis of the spindle 9 and 5 has a cover plate 25 removably held thereon by means of screws 26. A square or rectangular groove 27 is formed in the upper portion of the extension 22 and extends the entire length thereof, the upper side of the 10 groove being covered by the plate 25 and a longitudinally movable tool holder 28 being held therein.

The lower portion of the extension is bored and threaded as at 29, to receive the 15 tool operating screw 30 for moving the tool holder 28 backward and forward in the extension 22, the outer end of the screw 30 having a flange 31 formed thereon, as shown in Figs. 1 and 6, which engages a transverse 20 groove 32 formed in the lower side of the tool holder 28. Thus when the hand wheel 33, which is carried on the outer end of the screw, is turned, the screw is moved either 25 backwardly or forwardly of the extension 22, depending upon the direction of movement of the wheel, and the tool holder 28 is moved thereby, by reason of the connections described. The inner end of the tool holder 28 has a transverse bore for receiving and 30 holding the cutting tool 34 which is immovably held in the holder by means of a suitable set screw 35, as shown in Fig. 1. The elevation of the tool holder 28 is such that the cutting edge of the tool 34 will be 35 in the plane of the horizontal center line of the spindle 9 and valve 19.

It is obvious that when the spindle 9 is turned by means of the crank 10 for rotating the valve 19, and the proper position of the 40 valve 19 on the spindle has been adjusted by means of the screw 14, the tool 34 may be set forward in the holder 28 so that the cutting edge thereof is in proper position for cutting, and the tool holder may be moved in the extension 22 by turning the hand wheel 33, thus moving the tool backward and forward 45 over the edge of the valve.

The valve 19 may be ground by means of the mechanism shown in Figs. 7, 8 and 9, after 45 first removing the screw 30 and the hand wheel carried thereby from the extension 22. In such case, the tool holder 28 may be provided with a longitudinal bore 36 to revolvably receive a shaft 37 which carries at its 55 outer end a grooved pulley 38 and at its inner end an emery wheel 39, the latter being held on the shaft in the usual manner by means of the collar plate 40 and nut 41. A rack 42 may be formed on the lower side of the tool holder 28 and a suitable groove 43 60 may be formed in the extension 22 to receive the rack. A pinion 44, carried by a shaft 45 having a bearing in the front side of the extension 22, is suitably mounted in a transverse bore 46 in the lower portion of the ex-

tension so that the teeth thereon will mesh with those of the rack 42, and a cap 48, serving as an additional bearing for the opposite end of the shaft 45, is secured to the rear side of the extension by means of screws 70 49. A hand wheel 50, similar to the one 33 on the other form of device previously described, is provided on the outer end of the shaft 45 for turning the pinion 44.

When the hand wheel 50 is turned, and the 75 pulley 38 is suitably connected for operation by means of a belt leading to the lathe or other source of power for operating the grinding wheel 39, the pinion 44 is rotated, thus moving the rack 42 and tool holder 28 80 backward or forward, as the case may be, and the grinding wheel is moved over the surface of the valve, as illustrated in Fig. 7.

During the operation of the grinding wheel, it is of course necessary to turn the 85 spindle 9 so that an even smooth surface may be formed on the tapered portion of the valve, one hand of the operator being used in such case for turning the crank 10 and the other for turning the wheel 50. 90

While two forms of tool holders are shown and described, one for the cutting operation and the other for the grinding operation, it is possible to use the same tool holder for both operations, by providing the cutting 95 tool holder 28 with the longitudinal bore for the shaft 37, as the rack 42 will not in any way interfere with the operation of the screw 30, but when used as a cutter, it is necessary to remove the pinion 44 and hand wheel 50 so that the screw 30 may be inserted in the extension for moving the tool holder 28. Of course the greater convenience may be afforded by providing two separate tool 100 holders, each holder properly equipped with its respective turning or grinding elements, for in such case, when the cover of the extension is removed, either form of holder may be quickly inserted in position in the tool holding extension and it will not be 110 necessary to wholly or partially disassemble either of these units for making up a complete working unit for the other operation. 115

It should be understood that in the event of the valves 19 being provided with integral or non-detachable stems, the valves may be as readily cut and ground in my machine as otherwise, for the stems in such case may be inserted in the bearings 2 and 3, and the crank 10 may be placed on the valve stems 120 together with the spring 21 and collar 20, the upper bearing caps being removed for inserting the valve stems in the bearings.

What I claim is:

1. A valve finishing tool comprising a 125 base having head and tail stock bearings formed thereon and a vertical extension in alignment therewith, a valve stem adapted to receive a valve rotatably supported in said bearings, means on said stem for ro- 130

tating the valve and stem, an adjustable centering pin supported in said extension for centering the valve in operating position, means for maintaining a resilient engagement between said valve and pin, a tool post rigidly held on said base, a tool holder movably disposed in said post for regulating the engagement of the cutting tool with the valve, and means for moving said tool holder, as set forth.

2. A valve finishing machine comprising a base provided with bearings for rotatably supporting the valve stem, resiliently acting means for centering and limiting the thrust of the stem in said bearings, a tool holder movably disposed at an angle relative to the axis of said valve stem, an elongated screw movably supported on said base and having a collar engaging a groove in said holder for moving the holder therewith relative to said base, and means attachable to said valve stem for rotating the valve during the finishing operation.

3. A valve finishing machine comprising a base having integrally formed valve stem bearings and tool holder support for supporting said elements in diverging planes, a

valve stem adapted to receive a valve rotatably held in said bearings, an extension on said base alined with said bearings and provided with means for adjustably engaging the end of said valve stem, means on said valve stem intermediate of said valve and the adjacent bearing for holding said valve stem in engagement with said adjustable holding means, a tool holder adjustably supported on said base for engagement with said valve, means for moving said tool holder in its support, a cutting tool held on the end of said tool holder, and means for rotating said valve.

4. A valve finishing machine comprising an integral valve and tool holder support, a rotatably mounted valve stem on said support adapted to receive a valve, said tool holder being supported for longitudinal movement, means for moving the tool holder relative to the valve, and a cutting tool supported on said tool holder.

FREDERIC C. WILLIAMS.
